UNITED STATES PATENT OFFICE

ALBERT COLWELL NORTON, OF BERKELEY, CALIFORNIA, ASSIGNOR TO CALIFORNIA CORRUGATED CULVERT CO., OF BERKELEY, CALIFORNIA, A CORPORATION OF CALIFORNIA

FLUME

Application filed April 30, 1932. Serial No. 608,395.

The present invention relates to sheet metal flumes and more particularly to the supporting frames therefor, known in the art as substructures.

5 The principal object of the invention is to save weight and cost. My novel form of flume and substructure permits the use in the latter of fewer and lighter members, resulting in a considerable saving not only in weight but also in cost of manufacture and assembly. Another object is to provide means, without the addition of extra parts, for accommodating differences in longitudinal expansion of the flume trough and the substructure, especially when the latter is constructed of metal.

Other objects and advantages of the invention will become apparent from the following specification, which should be read with the understanding that changes, within the scope of the claims hereto appended, may be made in the form, construction and arrangement of the several parts described and illustrated, without departing from the spirit of the invention as defined in said claims.

Reference will be made to the accompanying drawing, in which

Fig. 1 is a side elevation of a flume embodying a preferred form of the invention.

Fig. 2 is a transverse section taken on the line 2—2 of Fig. 1 and enlarged.

Fig. 3 is a transverse sectional detail of a modification of the invention showing the use of a wooden substructure.

In the drawing, the reference numeral 1 designates the trough of my flume which may be made according to standard practise in sections connected together by any suitable transverse joints. The trough 1 is supported by the customary suspension rods 2, whose upper ends are connected with longitudinal beams or stringers 3. When the substructure is metal, as shown in Figs. 1 and 2, the stringers 3 are preferably channel section members, and the preferred means for hanging the trough therefrom comprises plates 4 having their outer ends 5 bent downwardly and inwardly to hook over the outer upper edge of the channel member 3. The ends of the suspension rods 2 pass through

the plates 4 and are held and tightened thereto by nuts 6. The inner ends of the plates 4 are bent downwardly, as shown at 7, to retain the upper edge of the trough in position. At the joints between trough sections, the usual compression member is placed inside the trough parallel to the rod 2 with its ends bearing against the plates 7. Tightening up the rod 2 clamps the lapped ends of the adjoining trough sections tightly between said rod and the compression member. Such joints are not material to the present invention, and being well known in the art, have been omitted from the drawing.

When the longitudinal stringers are of wood, as shown at 3' in Fig. 3, the rods 2 may extend directly through said stringers, the nut 6 bearing against a washer 8 on top of the stringer, and a plate 4' being placed below the stringer to bear against the upper edge of the trough. A tubular metal bushing 9 may be provided around the rod 2 within the stringer 3' to take the compression between the nut 6 and the plate 4'.

It is well known in the art that sheet metal flumes, when loaded, tend to assume a cross-sectional shape approximating a hydrostatic catenary. When the flume is initially constructed in semicircular form, its distortion under load to approximate catenary form produces a horizontal force upon the supporting stringers tending to twist them and draw them inwardly toward each other. In the usual types of flumes, this horizontal force is resisted partly by making the stringers sufficiently heavy, but principally by the use of closely placed crossbars extending horizontally across the top of the flume, and connected at their ends with the longitudinal stringers. These crossbars, which are placed approximately three feet apart in flumes under twelve feet wide, and eighteen inches apart in flumes of greater width, add materially to the weight and cost of the entire structure, because they must be heavy enough not only to resist the compression loads placed upon them, but also to support their own weight. In flumes twenty-one feet wide, for example, the crossbars, when made of

wood, are commonly ten by ten inches in cross section.

The specific shape of the trough forms the subject matter of my copending application for Letters Patent for sheet metal flume troughs and method of forming the same. In the present application it is sufficient to describe the trough as having a rounded bottom and divergent sides, such shape approximating a hydraulic catenary, and being approximately that which the trough naturally assumes when loaded. The essence of the present invention resides in tilting the stringers 3, as shown in Figs. 2 and 3, to place them approximately parallel to the upper portions of the sides of the trough. This tilting of the stringers, which is between fifteen and seventeen degrees from the vertical, brings them approximately parallel to the direction 20 of the force exerted upon them by the weight of the water in the trough, and causes them to be loaded almost entirely in the direction of their depth or greater cross sectional dimension. The stringers are therefore relieved of any transverse force tending to twist them or bend them laterally, and on this account can be made of lighter material than is customary in the usual construction. It is also possible to greatly reduce the number and 25 increase the spacing of the crossbars, as the latter are required only to stiffen the longitudinal stringers and not to resist any considerable horizontal force. I have found it possible to reduce the weight of the substructure as much as fifty per cent by this construction without any sacrifice of strength or rigidity.

The tilting of the stringers 3 enables me to use a sectional system of movably connected self-supporting units for the substructure, as illustrated in Fig. 1. Each stringer section is supported by a Y-shaped post 10, and its ends are slightly spaced from the ends of the adjacent stringers, as indicated at 11. Bolted 45 connecting plates 12 join the ends of adjacent stringers, and the bolt holes in at least one end of each plate 12 are elongated, as shown at 13, permitting a small amount of relative longitudinal movement between the stringers, 50 to allow for expansion and contraction of the metal. The two stringer sections upon opposite sides of the flume are braced together preferably by two crossbars 14, there being one such crossbar at the upper end of each 55 arm of the Y-post 10. That portion of the substructure between the two joints 11 therefore becomes a self-supporting unit, whose weight is carried by the two Y-posts 10, one on each side, and each such unit need be connected with the adjacent units only by the expansion connections 12. As a convenient means for mounting the stringers 3 upon the upper end of the Y-posts 10, I prefer to secure brackets or plates 15 to the stringers, by welding or otherwise, and to bolt the arms of the

Y-posts to said plates. Cross bracing, not shown, may be used between the lower portions of the opposite Y-posts if desired.

When the substructure is made of wood, as illustrated in Fig. 3, the stringers 3' may be supported by any suitable members such as wooden posts, one of which is indicated at 10'. The tilting of the stringers 3', just as in the case of the metal stringers 3 described above, permits the use of lighter members, and reduces the number of crossbars required. Obviously, the means shown in Fig. 2 for attaching the suspension rods 2 to the stringers may be used with wooden stringers instead of the means shown in Fig. 3.

The initial forming of the trough 1 to approximate catenary or natural load supporting shape reduces to a minimum its distortion under load. There is some slight change in curvature with variations in load, but such change is negligible compared with the distortion of a semicircular trough when first loaded. The minimizing of distortion not only reduces leakage at joints and increases the life of the trough and any protective coating thereupon, but also eliminates deleterious bending of the suspension rods 2. In semicircular flumes the upper ends of said rods, where they are attached to the substructure, are vertical, and distortion of the trough necessarily results in bending of said rods, a condition which has been met in the past by making the upper portions of the rods of heavier material. In my improved construction, the rods can be of the same size throughout, thus effecting a further saving in weight and cost of manufacture.

The above described form of the trough and the tilting of the longitudinal stringers to the same angle as the upper side portions of said trough, enables said stringers to support their load in the most efficient manner, and they can therefore be made of minimum size. They need have only sufficient lateral strength to make them stiff, with the assistance of a comparatively small number of crossbars, since they are loaded almost entirely in a direction parallel to their widest faces, and are not subjected to twisting forces. The greatest saving in weight and cost, however, comes from the reduction in the number of crossbars required. For example, under standard construction, the flume section shown in Fig. 1 would require five crossbars, one crossbar being customarily placed at each suspension rod. With my improved construction, however, only two crossbars are necessary, thus effecting a saving of sixty per cent.

I claim:—

1. A flume comprising a sheet metal trough initially formed to approximate catenary cross sectional curvature, and a pair of longitudinally disposed supporting members between which said trough is suspended, said

members having greater depth than width and being tilted about their longitudinal axes to a position approximately parallel to the upper portions of the sides of said trough.

6 2. A flume comprising a sheet metal trough having a rounded bottom and divergent sides, and a pair of longitudinally disposed supporting members between which said trough is suspended, said members having greater 10 depth than width and being tilted about their longitudinal axes to a position approximately parallel to the divergent sides of said trough.

15 3. A flume comprising a sheet metal trough, and a pair of spaced longitudinal stringer members between which said trough is suspended, said stringers having greater depth than width and being tilted about their longitudinal axes to cause their tops to diverge at angles between fifteen and seven- 20 teen degrees from the vertical.

25 4. A flume comprising a sheet metal trough having a rounded bottom and divergent sides, a pair of spaced longitudinal stringer members having greater depth than width and being tilted about their longitudinal axes to a position approximately parallel to the sides of said trough, and transverse rods extending beneath said trough for suspending it from said stringers, the upper ends of said rods 30 being parallel to the sides of said trough and passing through said stringers.

35 5. A flume comprising a sheet metal trough having a rounded bottom and divergent sides, a pair of spaced longitudinal stringer members having greater depth than width and being tilted about their longitudinal axes to a position approximately parallel to the sides of said trough, transverse rods extending beneath said trough for suspending 40 it from said stringers, the upper ends of said rods being parallel to the sides of said trough, and connecting plates bearing upon the tops of said stringers, the outer ends of said plates being bent downwardly over 45 the outer edges of said stringers, and the ends of said rods passing through the inner ends of said plates.

50 6. A flume comprising a sheet metal trough having a rounded bottom and divergent sides, a pair of spaced laterally tilted, longitudinally disposed stringers of channel section positioned with their flat faces toward and approximately parallel with the sides of said trough, connecting plates bearing 55 upon the tops of said stringers and having their outer ends hooked over the upper flanges thereof, and transverse suspension rods extending beneath said trough, the upper ends of said rods being secured to the inner ends of said plates.

60 7. A flume comprising a trough and a sub-structure, said trough having a rounded bottom and divergent sides, and said substructure being formed of a series of self-sup-

porting relatively expansible and contractible sections, each section comprising a pair of spaced, longitudinally disposed stringers having greater depth than width and tilted about their longitudinal axes to a position 70 approximately parallel to the sides of said trough, means for suspending the trough between said stringers, a post for supporting each stringer, and means connecting the two stringers together; and means for movably connecting the ends of the stringers of each section with the ends of the stringers of adjacent sections, said stringer ends being spaced apart to permit independent longitudinal expansion and contraction of each section.

In testimony whereof I have signed my name to this specification.
